UNITED STATES PATENT OFFICE.

FRANK R. BATCHELDER, OF WORCESTER, MASSACHUSETTS, ASSIGNOR TO MILLS WOVEN CARTRIDGE BELT COMPANY, OF WORCESTER, MASSACHUSETTS, A CORPORATION OF MASSACHUSETTS.

PAD FOR SUSPENDERS AND OTHER ARTICLES.

No. 861,936.

Specification of Letters Patent.

Patented July 30, 1907.

Application filed December 24, 1906. Serial No. 349,268.

To all whom it may concern:

Be it known that I, FRANK R. BATCHELDER, a citizen of the United States, residing at Worcester, in the county of Worcester and State of Massachusetts, have 5 invented certain new and useful Improvements in Pads for Suspenders and other Articles, of which the following is a specification.

This invention relates to improvements in pads for use in connection with suspenders, and in other connections, and the object is to provide a woven pad in which the sleeve, by means of which it is adjustably attached to the suspenders or other articles, and the pad portions are formed of plies of fabric interwoven so as to produce a simple, neat and effective pad structure.

With the above object in view the invention consists in the novel features of construction hereinafter fully described, particularly pointed out in the claims, and clearly illustrated by the accompanying drawing, in 20 which

Figure 1 illustrates one form of my improved pad applied to suspenders; Fig. 2, a similar view showing another form of the pad, and Fig. 3, an enlarged detail view illustrating the manner of weaving the pad shown 25 in Fig. 2.

I have illustrated the improved pad in connection with suspenders used for supporting ammunition belts in which 1 indicates the main portion of the suspenders comprising a narrow strap formed of woven material 30 and of sufficient length to provide two strap portions or members 1'. The two strap portions are made adjustable by means of suitable buckles 2 and their ends carry loops or hooks 3 for attachment to the cartridge belt. The strap 1 passes through one slot of the double 35 metal loop 4, a short strap 5 passing through the other slot of said loop member, said short strap having hooks or loops 6 at each end for attachment to the cartridge belt. This strap 5 is made adjustable by means of a suitable buckle 7, and is prevented from disengaging 40 the metal loop 4 by a stud 8.

The pads illustrated in Fig. 1 are of woven fabric consisting of two plies, one of the plies being separated in the weaving for a portion of the width of the pad to form a longitudinally-extending sleeve of sufficient 45 width to receive one of the strap-portions 1'. A pad is thus formed consisting of a longitudinally-extending sleeve and a pad portion which projects a considerable distance beyond each longitudinal edge of the sleeve to provide a pad having a broad bearing surface. 50 Through the medium of the sleeves, the pads may be adjusted on the straps of the suspenders, as may be desirable. By use of these pads, the suspenders or other articles in connection with which the pads are used,

may be made very narrow and consequently considerably reduced in weight. At the same time, broad 55 bands or bearing surfaces are provided at the shoulders.

In Fig. 2, the shoulder pads are each formed of two plies of material 18 and 19, woven and bound together by means of binder threads, and a ply 20 separated in the weaving from the lower plies to form a sleeve to receive one of the straps 12 of the suspenders.

In Fig. 3, an enlarged detail view is shown of the manner of weaving the three plies. The two plies 18 and 19 are bound together by the binder threads 21 and the upper ply 20 is interwoven with the two lower plies, at the point 22. The binders 21 divide the two plies 18 and 19 into a series of tubes within each of which are eight dead threads 23 around which said two plies are tightly woven and bound so as to form a solid fabric base upon which the narrow portion of the 70 suspenders will rest after passing through the sleeve formed by the upper ply 20. It will be seen that the threads forming the upper ply 20 will, at the edges, where the latter is interwoven with the two lower plies enter under the binders 21 and pass around the dead 75 threads 23. The dead threads 23 at the ends of the pads are cut off and the two lower plies turned in one upon the other, and the ends securely stitched. The top ply is woven for a short distance independent of the lower ply, the end turned in upon itself and the 80 folds securely stitched, thus forming a neat opening or mouth for the sleeve. From the above description, it will be seen that the pad in this case is formed of three thicknesses of cloth interwoven, the two lower thicknesses being bound together to form a thick, soft pad, 85 while the third thickness forms a sleeve to receive the strap of the suspenders. The actual strain when in use is on the strap of the suspenders, which are comparatively narrow, which tends to cut or press on the shoulders of the wearer, and thereby cause great 90 discomfort. By having a pad, however, formed of a base or bearing surface of two thicknesses of cloth, a good cushion is formed so that even though the pull or strain upon the strap portions of the suspenders is severe, the 95 pads will give ample protection to the shoulders of the wearer.

The suspenders shown in Fig. 2 are formed of two strap portions 12 which are crossed and held together at their point of closing by a band or loop 13 which permits the play of one upon the other, this movement being limited, and the straps being prevented from disengagement by studs 14. The straps are made adjustable by means of buckles 15 and at their ends carry hooks 16 by means of which they may be connected to the belt.

From the above description, it will be seen that I

have provided a woven fabric pad comprising a longitudinally-extending sleeve and a pad portion projecting beyond each longitudinal edge of the sleeve, the sleeve and pad portion being interwoven.

5 Having thus fully described my invention, what I claim as new, and desire to secure by Letters Patent of the United States, is:

10 1. A woven fabric pad comprising a longitudinally-extending sleeve and a pad portion projecting beyond each longitudinal edge of the sleeve and interwoven therewith.

2. A woven fabric pad comprising a longitudinally-extending sleeve and a pad portion projecting beyond each longitudinal edge of the sleeve and formed of a plurality of plies of the material, the pad portion and sleeve being interwoven.

1 In testimony whereof I affix my signature in presence of two witnesses.

FRANK R. BATCHELDER.
